EDWIN AUGUSTUS HILL, OF TORONTO, ONTARIO, CANADA.

GLASS SHOW-CASE CONSTRUCTION.

1,410,919.

Specification of Letters Patent. Patented Mar. 28, 1922.

Application filed April 6, 1921. Serial No. 459,104.

To all whom it may concern:

Be it known that I, EDWIN AUGUSTUS HILL, of the city of Toronto, in the county of York, in the Province of Ontario, 5 Canada, have invented certain new and useful Improvements in Glass Show-Case Constructions, of which the following is a specification.

My invention relates to improvements in 10 glass show-case constructions and the object of the invention is, to devise means for preventing the longitudinal movement of the glass plates forming the top of the show-case so that they will not spread apart at 15 their abutting edges to separate at their point of junction, and it consists essentially of the following arrangement and construction of parts as hereinafter more particularly explained.

20 Fig. 1 is a perspective view of a portion of a glass show-case.

Fig. 2 is a plan sectional view through the 25 top portion of the top brackets showing the means for holding the top plates of the show-case together.

Fig. 3 is a perspective detail of the clip employed in connection with the top brackets.

Fig. 4 is a sectional detail showing means 30 for connecting a glass plate, set at an incline to a bracket such as 8.

In the drawings like characters of reference indicate the corresponding parts in each figure.

35 1 and 2 are glass plates forming the longitudinal wall of a show-case, 3 an end cross wall and 4 an intermediate cross wall which extends between the opposing vertical end edges of the plates 1 and 2 so as to protrude 40 slightly beyond the outer face of the plates 1 and 2. 5 and 6 are plates forming the top of the show-case, the line of junction between the plates 5 and 6 being placed over the top edge of the intermediate plate 4.

45 The outer longitudinal edges of the plates 5 and 6 are provided with notches 7 in proximity to each end of the plate. 8 and 9 are holding brackets. The bracket 9 comprises a portion 10 which extends around the vertical edge of the plate 3 and a portion 11 which extends around the adjacent longitudinal edge of the plate 5, and a substantially triangular shaped webbed portion 12 connecting the portions 10 and 11 together.

55 The bolt rod 13 extends through the web 12 and is connected to the corresponding por-

tion of a similar bracket on the opposite side of the show-case. The bracket 8 comprises a portion 14 extending around the vertical edge of the plate 4 and portions 15 and 16 60 extending around the longitudinal edges of the plates 5 and 6 and web portions 17 and 18 connecting the portion 14 with the portions 15 and 16. 19 and 20 are bolt rods which extend through the webs 17 and 18 65 and pass through the corresponding webbed portions of similar brackets located at the opposite side of the show-case. The brackets 8 and 9 as above described are of a construction which is commonly employed 70 and to which I do not lay any claim.

In order to prevent the longitudinal movement of the top plates 5 and 6 so as to prevent their drawing apart at their meeting edges, I have provided clips 21. The clips 75 21 are formed by a strip of metal bent into a U-shaped projection 22 intermediately of its length. The ends 23 and 24 shown bent at right angles to the main portion of the strip 21 are normally in a line with such 80 strip.

It will be noted on referring particularly to Fig. 2 that the notches 7 are located within the horizontal bracket portions 15 and 16 and a notch 7 is similarly located within 85 the bracket portion 11.

When the brackets 8 and 9 are placed in position, the strip 21 is placed within the bracket with the U-shaped projections 22 fitting into a notch 7, the strip 21 lying flat 90 against the edge of the glass plate forming the top of the show-case.

When in this position the ends 23 and 24 are bent outward into the position indicated holding the clip in place within the bracket, 95 the glass forming the top of the show-case being prevented from moving longitudinally by the notch 7 engaging the projection 22 which is held in a stationary position within the bracket portions 15, 16 and 11 by the 100 out-turned ends 23 and 24.

From this description, it will be seen that I have devised very simple means for securing the longitudinal and vertical cross walls of the glass show-case together and also provide simple means whereby any slippage of the top plates of the show-case within the holding brackets is eliminated.

What I claim as my invention is.

1. In a glass show-case, the combination 110 with two plates forming the top of the show-case, of a holding bracket adapted to form

edge embracing means for the longitudinal edges of the plates in proximity to their opposing ends, and a projection located within the edge embracing means and adapted to engage the edge of the glass plates.

2. In a show case, the combination with two plates forming the top of the show-case having depressions in their longitudinal edges and means for embracing such longitudinal edges and containing such depression, and a projection held in a stationary position within the embracing means and adapted to enter and engage such depression.

15 3. In a glass show-case, the combination with two plates forming the top portion of the show-case having notches in their longitudinal edges in proximity to each end, of

a bracket provided with a portion embracing the longitudinal edges of the top plates so 20 as to contain the aforesaid notches, and a metal strip of bendable material adapted to extend through such embracing portion and adapted to be bent outward at its ends against each end of the embracing portion 25 and provided with a projection intermediate of its length adapted to enter the corresponding notch of the show-case top plate.

4. In a show-case, the combination with the top plates and a bracket portion embracing the edges of such top plates, of lateral projections adapted to engage the top plate and each end of the embracing portion of the bracket to prevent longitudinal movement.

EDWIN AUGUSTUS HILL.
